US0D1020428S

(12) **United States Design Patent** (10) **Patent No.:** **US D1,020,428 S**
(45) **Date of Patent:** **** Apr. 2, 2024**

(54) **MULTI-TOOL KNIFE**

(71) Applicant: **Yangjiang Weigu Industry and Trade Co., Ltd.**, Yangjiang (CN)

(72) Inventor: **Weihong Guan**, Guangdong (CN)

(**) Term: **15 Years**

(21) Appl. No.: **35/515,707**

(22) Filed: **Nov. 11, 2022**

(80) **Hague Agreement Data**

Int. Filing Date: **Nov. 11, 2022**

Int. Reg. No.: **DM/224969**

Int. Reg. Date: **Nov. 11, 2022**

Int. Reg. Pub. Date: **Dec. 2, 2022**

(30) **Foreign Application Priority Data**

May 30, 2022 (CN) 202230326366.3

(51) LOC (14) Cl. **08-05**

(52) U.S. Cl.

USPC **D8/105**

(58) **Field of Classification Search**

USPC D8/99, 105; D22/149

CPC B26B 11/001; B26B 11/003; B26B 11/006

(57) **CLAIM**

The ornamental design for multi-tool knife, as shown and described.

DESCRIPTION

1. Multi-tool knife

1.1 : Front

1.2 : Back

1.3 : Left

1.4 : Right

1.5: Top

1.6: Bottom

1.7: Perspective

1.8: Perspective

1.9: Perspective

1.10: Perspective

Fig. 1.1 is a front view of multi-tool knife; Fig. 1.2 is a back view thereof; fig. 1.3 is a left view thereof; fig. 1.4 is a right view thereof; fig. 1.5 is a top view thereof; fig. 1.6 is a bottom view thereof; fig. 1.7 is a first perspective view in close state thereof; fig. 1.8 is a second perspective view in close state thereof; fig. 1.9 is a first perspective view in open state thereof; fig. 1.10 is a second perspective view in open state thereof.

1 Claim, 10 Drawing Sheets
